UNITED STATES PATENT OFFICE.

JACOB KOBOS, OF CHICOPEE, MASSACHUSETTS.

AUTOMATIC SAFETY-GUARD FOR ELEVATOR-WAYS.

SPECIFICATION forming part of Letters Patent No. 529,177, dated November 13, 1894.

Application filed August 13, 1894. Serial No. 520,185. (No model.)

To all whom it may concern:

Be it known that I, JACOB KOBOS, a subject of the Emperor of Germany, residing at Chicopee, in the county of Hampden and State of Massachusetts, have invented new and useful Improvements in Automatic Safety-Guards for Elevator-Ways, of which the following is a specification.

This invention relates to improvements in automatic safety guards for elevator ways, more particularly those of the class in which the gate is automatically raised when the elevator car is at, or about at, the floor, and which closes when the elevator car passes away from such floor, either above or below, as the case may be.

The object of the invention is to improve the safety devices especially with respect to the adoption therein of approved mechanical principles, to the certainty of the automatic operation, and to the simplicity of the constructions; and the invention consists in constructions and combinations or arrangements of parts all substantially as will herein-after fully appear and be set forth in the claims.

Reference is to be had to the accompanying drawings, in which—

Figure 1 is a perspective view showing the elevator way,—with the gate thereat,—with the automatically operative appliance, and showing the elevator car as rising ready to effect the automatic operation of the gate. Fig. 2 is a perspective view showing a fixture of the elevator car as seen at the opposite side from that shown in Fig. 1. Fig. 3 is a front view of the upper portion of the gate with movable devices thereon also showing the co-operation with the latter of a fixture on the elevator car which fixture is indicated in vertical section. Fig. 4 is a horizontal cross section of a vertical tube-like way at one edge of the gate showing the counterweight for the gate, therein, with the hinged foot and toe thereof. Fig. 5 is a vertical sectional view of the aforesaid tubular way with the counterweight having the hinged foot therein, said view being designed to indicate the gate-lifting action on the descent of the elevator car, a fixture of which latter is also shown. Fig. 6 is a view similar to Fig. 5 but more particularly arranged to show the capability of the elevator to rise without direct effect upon the

toe-provided counterweight. Fig. 7 is a plan view of a portion of the elevator car, with the fixture which co-operates with the aforesaid foot of the counterweight. Fig. 8 is a vertical sectional view somewhat similar to Fig. 5 but illustrating the manner in which the hinged foot of the counterweight recedes on the downward passage of the car from engagement with the coacting elevator car fixture, at the time when the gate has been raised. Fig. 9 is a perspective view showing the separate parts of the depending foot of the counterweight.

In the drawings, A, represents the floor of a building having the hatchway or elevator way, B, and C represents the elevator car of a common form and adapted to be operated in the usual manner.

D represents the safety gate at the one side of the elevator way, arranged to slide vertically on and between the vertical posts, a a². Upon the upper horizontal bar or part, b, of the gate are two bars d d arranged horizontally end to end and guided to slide horizontally toward and from each other. The outer extremities of these bars normally have engagements with the vertical racks f f on the side posts a a², and the springs g g normally hold said bars d d with their outer ends in engagement with said racks. At their inner extremities the bars d d are provided with transverse projections h h the outer edges of which are inclined upwardly and inwardly as at 10 10 and downwardly and inwardly as at 12 12. It will also be noted that the inner ends of the part d have a slight separation. One of the said posts a is hollow or tubular with the slot i through the side which is at right angles to the plane of the gate, and as seen in Figs. 4 and 5. In this tubular post is a counterweight j connected by the sheave guided cord or chain k with the gate d.

The elevator car has the offset arms, or support m which carries the trough-like shoe, n the opposite inner sides of which are, between their top and bottom, inwardly convergent. See Fig. 2. Now as the car in rising, approaches the level of the floor, the said shoe engages the inclined projections h h of the bars d d, and while in such engagement the initial action may be to cause the said projections h h to be moved toward each other to

some extent, and thereby draw the bars so as to nearly or quite disengage their outer ends from the racks. The effect of the springs $g\ g$ will be to insure the retention of the engagement between parts $h\ h$ and n to lift the gate to its limit. When the limit of upward movement of the gate is reached which movement may be limited by the abutment studs, 25, 25, seen in Fig. 1, the then continued upward movement of the car and its shoe, n , through the cam action of the engaging surface of the latter, cause the projections $h\ h$ to be so forcibly crowded toward each other as to permit the shoe to pass over, between 15 and free from them, whereupon the bars are then free to be outwardly forced under the reaction of the springs $g\ g$ to their engagement with the racks, $f\ f$ (the teeth of which are not ratchet-like, but rounded). The gate 20 will now descend by reason of its weight, the outer ends of the bars, $d\ d$, clicking down over the rack bars $f\ f$, this action being to prevent the too precipitate descent of the gate. The descent of the car toward and into proximity to the same floor again causes the lifting of the gate, but in this case it is by reason of the coaction of the projection q on the elevator car with the foot t of the aforesaid counterweight j . It will be seen that the foot 25 of the counterweight is practically hinge-connected to the weight, and it has the toe t^2 hinge-connected to the bar which constitutes the foot, the joint being of a well known form which allows the toe to swing up on pressure 30 from below, but which remains rigidly in its right angular position and unaffected by any downward pressure thereupon. The toe t^2 is downwardly and inwardly inclined. The foot has its back running alongside the rib u in 35 the tubular post, which rib at a suitable relative point as seen at v is cut away or recessed, and in part covered by the plate spring, w . As the car descends, its member q in impinging upon the top of the toe t^2 causes the foot 40 and counterweight to be lowered and the gate to be raised. When the car has gone so far as to render the gate properly opened the foot t will have been, by the member q , carried down so far as to bring it opposite the recessed part, v of the rib u whereupon the transverse pressure exerted by the cam-like engagement between the elevator member q and the toe, causes,—as is now permitted,—the foot to swing on the weight within the 45 recess leaving the said member q to pass clear from and below the said foot, which then under the reaction of the spring, w or of its proper poising to again assume its normal position, with its toe projecting through the slot,

i ; and of course just as soon as the engagement between said parts q and t^2 is broken, the gate will by its own sufficient weight drop to its safety position.

Having thus described my invention, what I claim, and desire to secure by Letters Patent, is—

1. The combination with the vertically movable gate having the outwardly movable bars $d\ d$ with the transverse projections $h\ h$ at their adjacent inner ends, the springs $g\ g$ for forcing the bars outwardly and the vertical rack bars with which the outer extremities of said bars engage, of the elevator car having the trough-like member or shoe n with the inclined opposite sides substantially as and for the purposes described.

2. The combination with the elevator car having the member q and the tubular post with the slot i and rib u having the recess at a suitable point in its height of the gate, the counterweight in said tubular post and having a cord and sheave guided connection with the gate, the foot t having a hinge connection with the weight and having the articulated toe t^2 substantially as described, which projects through said slot into the path of travel of the said member of the car substantially as described.

3. The combination with the elevator car having the member q , the tubular post with the slot i and having the rib with the recess at a suitable point in its height, and the spring applied in the said tubular post at said recess, of the gate, the counterweight playing in said tubular post, the hinged foot connected to the weight and sliding alongside said rib and having the articulated toe substantially as described which projects through said slot into the path of travel of said member of the car, substantially as described.

4. The vertically movable gate having the outwardly movable members $h\ h$ and springs for maintaining them in their outward dispositions, the tubular post provided with the slot i , the counterweight cord connected with the gate and playing in said tubular post and having the hinged foot t with the articulated toe t^2 in combination with the elevator car having supported at an upper portion thereof the trough-like member n with the inwardly and downwardly convergent opposite sides, and also having the member q to coact with said toe, all substantially for the purposes set forth.

JACOB KOBOS.
